UNITED STATES PATENT OFFICE.

WINFIELD S. ROGERS, OF BANTAM, CONNECTICUT, ASSIGNOR TO NELLIE SCOTT
ROGERS, OF BANTAM, CONNECTICUT.

GRINDING MACHINE.

Application filed February 14, 1925. Serial No. 9,237.

To all whom it may concern:

Be it known that I, WINFIELD S. ROGERS, a citizen of the United States, residing at Bantam, in the county of Litchfield and State of Connecticut, have invented certain new and useful Improvements in Grinding Machines, of which the following is a specification.

This invention relates to grinding machines, and more especially to that type known as "centerless."

Its primary object is to provide a centerless grinder of economical construction, whereby one abrasive wheel shall do the work usually required of two. Other objects are to provide a centerless grinder equipped with means whereby the waste material may be washed away ahead of the work; that shall conveniently dispose of the washing material so used; and that shall speedily accomplish the work for which the machine is designed.

To accomplish these objects, I have provided a machine comprising a frame, a vertical abrasive wheel, suitable power means connected with said wheel, a work-guide attached to a movable block with suitable adjusting means, facilities for feeding work to the machine in a vertical position, a method for cooling said wheel and for keeping its grinding surface and the work free from grit and other waste material.

In the drawings, Figure 1 is a longitudinal vertical section of the machine herein described, the grinding wheel in elevation; Figure 2 is a top view of the same; and Figure 3 is a detail front-view of the mobile block and work-guide, taken at a right-angle to its normal position.

40 A represents the abrasive wheel, B the work-guide, C the movable block, D a screw with handle, for adjusting B and C in relation to A, E a conduit for the cooling and washing element, F an electric motor, H pieces of work passing through the machine, J a receptacle for the cooling element, K an opening giving access to J, L the frame, M lag-screws, and N slots in B for adjusting purposes.

45 The use of a vertical grinding wheel furnishes a more effective means for removing the grit and other fines from the abrasive wheel and from the object being ground, because of the application from overhead of the cooling liquid, than is possible with any

other type of wheel. It also provides a superior facility for feeding the work, either automatically or manually.

The movable block C contains a concave V-shaped work-guide B, that is capable of being set at a tangent, and is provided with curved slotted apertures N, whereby B is capable of rotary adjustment for fixing the tangential degree required. The work-guide, by reason of this tangential concavity, is capable of regulating the period during which the work H is to be subjected to the operation of the grinding-wheel A; the greater its angularity to the vertical surface of said wheel, the shorter the period of grinding, 70 and eo converso.

The motor F is shown as a preferred means for furnishing power to the wheel A. The opening K may be of any desired shape or in any desired location, and is preferably 75 provided with a closure.

In operation, the machine is set, by means of the wheel and screw D, with its work-guide B at the desired distance from the grinding-wheel A, with reference to the size 80 of the object to be ground or the size to which it is to be reduced; the work-guide adjusted to the proper angle, the power turned on, and the work is fed to the machine by placing the objects H in the V- 85 groove of the guide B. Any suitable means, such as a hopper and trough, may be employed as an automatic feeder, or the feeding may be by hand. The goose-neck E illustrates a convenient means for applying 90 the cooling and washing medium, either by gravity or forced from a pump. The pump may be integral with the machine, and the cooling and washing medium re-used from the pan J. The finished work may be allowed to fall into said pan, or it can be diverted in another direction.

Many of the features herein shown and described are already familiar, and are not alleged to be novel.

I claim:

1. A grinding machine comprising a single abrasive wheel rotatable upon a vertical axis, its grinding surface being parallel to the said axis, a vertical mobile block with an 105 adjustable work-guide thereon, said wheel being capable of rotating and grinding the surfaces of cylindrical objects fed downwardly between said wheel and said guide, and means for supplying a cooling-medium 110

to the said grinding-wheel and to the object being ground, at and in advance of their point of contact.

2. In combination, a single abrasive wheel revolvable upon a vertical axis, the cutting surface being the periphery of said wheel, an adjustable work-guide capable of holding and downwardly directing in a substantially vertical course against said cutting surface

the object to be ground, a means for applying a cooling medium to said cutting surface vertically downward so as to positively free the grinding wheel and the work from all fines and grit, and a frame-work containing and supporting said members. 10 15

In testimony whereof I have hereto affixed my signature.

WINFIELD S. ROGERS.
